UNITED STATES PATENT OFFICE.

CHARLES F. TEBBETTS, OF BOSTON, MASSACHUSETTS, ASSIGNOR OF ONE-HALF TO CHARLES E. BROWNELL, OF NEW BEDFORD, MASSACHUSETTS.

LABELING-MACHINE.

SPECIFICATION forming part of Letters Patent No. 634,708, dated October 10, 1899.

Application filed September 29, 1897. Serial No. 653,444. (No model.)

To all whom it may concern:

Be it known that I, CHARLES F. TEBBETTS, of Boston, in the county of Suffolk and State of Massachusetts, have invented certain new and useful Improvements in Pneumatic Labeling-Machines, of which the following is a specification.

My invention relates to new and useful improvements in means for applying labels to bottles or other articles; and its main object is to transfer from a stack of labels one label at a time and to apply the same to the article to be labeled.

My invention consists of certain novel features hereinafter described, and particularly pointed out in the claims.

In the accompanying drawings, which illustrate a construction embodying my invention, Figure 1 is a side elevation of my improved labeling-machine, showing the parts in their normal positions before the apparatus is started. Fig. 2 is a plan view of the same. Fig. 3 is a longitudinal sectional view through the apparatus with parts in full lines and showing the apparatus in position to apply a label to the bottle or other article. Fig. 4 is a vertical cross-sectional view taken on the line XX, Fig. 3. Fig. 5 is an enlarged detail sectional view of the label-box and carrier for carrying the labels from the label-box to the article to be labeled and showing a label lifted to the carrier which is starting on its travel to the article to be labeled. Fig. 6 is an enlarged plan view of the labeling-receptacle. Fig. 7 is a cross-sectional view through the label-carrier on the line X' X', Fig. 8. Fig. 8 is a plan view of the bottom plate of the label-carrier. Fig. 9 is a longitudinal vertical section through the plate on the line X² X², Fig. 10. Fig. 10 is a plan view of the bottom plate of the label-carrier and showing the perforations arranged differently from that shown in Fig. 8.

Like letters of reference refer to like parts throughout the several views.

Located on one end of the base-plate A, on the tracks A' there is a label-box B in which is stacked a number of labels B', and over the front end of the same is an opening B², and the side of the box B is closed by a suit-

able door B³. The labels B' are placed upon a movable plate B⁴, and said plate is pressed upwardly by means of springs B⁵, secured in the bottom of the box at B⁶, and the object of said springs B⁵ and movable plate B⁴ is to hold the labels in the upper part of the box. The label-carrier C, moving upon suitable glide-supports C', is adapted to coöperate with the label-box B. This label-carrier C has two hollow compartments D and D', and the bottom plate C² is held in place by a dovetailed joint, (see Fig. 7,) and its forward end contacts at D² with the piece D³, extending across the bottom of the box at the front. (See Fig. 3.) The rear half of said plate C² is provided with perforations C³, and the forward end is hollowed out or recessed, as shown at C⁴ in Figs. 8 and 9, for a purpose hereinafter described. The perforations C³ (shown in Fig. 10) are adapted for a label having a rounded or curved front edge, while the perforations shown in Fig. 8 are adapted for labels having straight front edges, the object being that the front row of perforations shall correspond in shape to the shape of the front edge of the labels, so that none of the perforations shall be uncovered when a vacuum is produced to lift a label from the label-box and carry it to the article to be labeled. Otherwise if some of the perforations are open the vacuum would not have the same force or effect as where the perforations are all covered.

On the partition D⁴, which separates the compartments D and D', there is a flap-valve D⁵, which when held to its seat closes the opening D⁶ between the compartments D and D'. A flexible tubing E is connected at E' to the compartment D of the label-carrier C and at its other end opens into the piston-chamber J' of the pump J at E². Also communicating with the compartment D at the point F' is another flexible tubing F, the opposite end of which communicates with the piston-chamber J' at the point F² just below the entrance of the tube E into the piston-chamber J'.

To one end of the label-carrier C there is firmly secured at G the piston-rod G', to which at its other end is secured the piston G²,

adapted to reciprocate in the piston-chamber G³, suitably supported on the side of the chamber J by the lugs F³, secured to the supporting-frame J¹⁰. A flexible tube H communicates with the piston-chamber G³ at the end opposite the label-carrier C and opens at H' into the piston-chamber J. Located in the line of travel of the label-carrier is a box K, containing mucilage or other adhesive material, and within said box is located the brush K², carried by the shaft K' and adapted to move up and down in the slot K⁸. On the opposite sides of the mucilage-box K are the bearings K⁴, having a shaft K', and said bearings are mounted on the upper end of the rod K⁵, and around the lower reduced end of which is located the coiled spring K⁶, which bears against the enlarged portion of the rod K⁵, at its upper end 20 and at its lower end bears against the guide K⁸, which guides the lower end of said rod K⁵ in its vertical movements, while the guide K⁷ guides the upper end of the rod K⁵ in its vertical movements. On the lower end of 25 the rod K⁵ the nut K⁹ is screwed and is in contact with the under side of the guide K⁸, and by means of said nut the rod K⁵ can be raised or lowered when desired. A right-angle arm K¹⁰ is mounted on the pivot K¹¹ in 30 the side of the box K, and its outer end bears upon the shaft K'. A flat spring K¹² is secured in the head of said pivot, and its free end bears against the pivoted finger K¹³, having a suitable friction-roller on its end, and the object of said spring is to move the brush K² into the position shown in Fig. 3 to prevent the smearing of mucilage on the bottom of 35 said plate as the label-carrier returns from the article labeled to the label-box by reason of the spring K¹² acting on the finger K¹³, which, acting on the arm K¹⁰, in turn presses downwardly the shaft K¹¹ and compresses the spring K⁶, which is of less tension than the spring K¹². Upon the travel of the label-carrier C 40 from the label-box to the article to be labeled one of the rubber strips C⁵ on the bottom of the label-carrier C strikes the friction-roller on the end of the finger K¹³, and as the carrier moves from the label-box toward the article to be labeled the finger K¹³ being pushed 45 forward, as shown in Fig. 1, overcomes the tension of the spring K¹², and the spring K⁶ moves the brush K² upwardly in position to apply adhesive material to the under side of the label, which is being transferred from the label-box to the article to be labeled. Owing 50 to the recess C⁴ in the front of the bottom plate C² the brush K² does not apply any mucilage to said plate until the rear portion 55 of said plate C² with the label arrives over said brush, which then applies mucilage or other adhesive material to the under side of the label as it travels toward the article to be labeled. As the label-carrier passes beyond 60 the mucilage-box the brush and coöperating parts assume the position shown in Fig. 3, owing to the tension of the spring K¹²,

as previously described, so that as the label-carrier returns toward the label-box no mucilage is applied to the under plate C².

The labeling-receptacle L, in which the articles to be labeled are placed is provided on its opposite ends with two yokes L', supported by vertical rods L², having an enlarged upper portion which is guided by the guide 70 L³, and the reduced lower portion is guided by the guide L⁸ in its vertical movements. The spring L⁷ surrounds the reduced portion of the rod L² and bears at its upper end against the enlarged portion of said rod L² 75 and its lower end bears against the guide L⁸, and its object is to provide a yielding vertical movement to the opposite yokes L'. On the lower end of said rod L² there is located the nut L⁹, by means of which the vertical 80 position of the yokes L' can be regulated, depending upon the greater or smaller diameter of the article being labeled. Within the labeling-receptacle are two rolls L⁴, which support the bottle or other article, and said 85 rolls are provided on the opposite ends with pintles L⁵, which are journaled in the recess L⁶ in the opposite yokes L'. With the mechanism thus far described there is adapted to coöperate an air-pump J, 90 consisting of the piston-chamber J', in which there is adapted to reciprocate the plunger J², to which there is pivotally connected at J³ the connecting-rod J⁴, also pivotally connected at J⁵ to the hub J⁶ of the driving-wheel J⁷, fast on the shaft J⁸, having bearings J⁹ in the supporting-frame J¹⁰. To one side of said driving-wheel J⁷ there is located the driving-pulley J¹¹, also fixed fast on said shaft J⁸, and alongside of said pulley J¹¹ is a loose 95 pulley J¹², which when the apparatus is not in operation receives the belt J¹³, and no power is communicated to the apparatus; but when it is desired to operate the apparatus the belt J¹³ is shifted onto the pulley J¹¹, whereby the 100 apparatus is set in motion by the power communicated.

The arrangement shown in Fig. 5 is identical with that shown in the other views, except that the label-carrier is increased to 105 carry labels of a size sufficiently large to completely surround a bottle, can, or other article to be labeled. In this arrangement the labeling-receptacle L is adjusted so that the extreme rear end of the carrier C with the 110 label comes over the bottle or other article at the end of its forward movement in the same manner as that shown for a smaller label in Fig. 3.

By means of the adjusting-screw O the bottle in the labeling-receptacle can be adjusted so that the label can be applied in any desired position on the bottle.

The operation of the apparatus is as follows: With the parts in the position shown 115 in Fig. 1 the plunger J² has just begun its upward stroke, and in said upward movement it has drawn the air into the piston-chamber J' from the chamber D through the flexi-

ble tube F and from the piston-chamber G³ through the flexible tube H, and the result is that a label has been lifted to and held on the plate C² over the perforations C³ by the vacuum in the compartment D, the valve D⁵ being closed by said vacuum, so that there is no drawing of air through the rear perforations in the compartment D', as said perforations are not located at the beginning of the movement of the carrier C over the exposed ends of the labels B', and consequently it is necessary that there should be no draft through said perforations, as such an arrangement would destroy the effect of the vacuum in the compartment D. Owing to the suction of the air through the tube H the carrier has just started on its forward movement, as shown in Fig. 1. As the piston J² continues its upward movement it continues to draw air from the piston-chamber G³ through the tube H into the piston-chamber J' and into the same chamber through the tubes E and F from the compartment D of the carrier C, so that by reason of the exhausting of air from the piston-chamber G³ the piston G² is moved to the position shown in Fig. 3, and the label is held thereon by means of the vacuum in the hollow compartment D. In the forward movement of the carrier from the position shown in Fig. 1 to that shown in Fig. 3 one of the rubber strips C⁵ on the bottom of the label-carrier, acting on the finger K¹³, as shown in Fig. 1, moves it to the position shown in Fig. 1, so that the spring K¹² does not affect the right angle arm K¹⁰, and consequently the spring K⁶ moves upwardly the mucilage-brush K², as shown in Fig. 1, but as the bottom plate C³ is recessed, as shown at C⁴ in Figs. 8, 9, and 10, no mucilage is applied to that portion of the plate, as the brush does not reach sufficiently high, but as the rear portion of the plate which extends lower comes over said brush the label previously referred to is held thereon over the perforations, and the mucilage-brush K², coming in contact with the under side of the label, applies mucilage or other adhesive material thereto, and as the label extends to the extreme end of the box, as shown in Fig. 3, the brush cannot apply mucilage to anything but the under side of the label, and as soon as the box has passed beyond the finger K¹³ the spring K¹², acting on said finger, moves the brush K² into the position shown in Fig. 3 sufficiently below the line of travel of the carrier C, so that upon its return movement no mucilage is applied to the plate C³. The rubber strips C⁵ are beyond the brush and therefore do not receive any mucilage. The label-carrier C having passed the mucilage-box comes over the labeling-receptacle L and moves upward until it has reached a position with its rear end and the rear end of the label over the bottle M, as shown in Fig. 3, at which point the plunger J² has reached its upper position and air is taken into the chamber J' of the pump J through the inlet J¹⁴, and owing to the rapidity with

which atmospheric air rushes into a vacuum a large amount of air passes into said chamber J', and this admitted air is compressed by the downward stroke of the plunger J², and, passing through the tube H, starts the label-carrier C on its return movement toward the label-box B and passes through the tube E and then through the compartments D and D' and blows the label from the label-carrier C as said carrier is started on its movement toward the label-box B. The tube F is provided with a leather flap-valve or any other suitable check-valve F³, which opens when the plunger J² is moving upwardly to produce a vacuum in the compartment D; but when the plunger J² is moving downwardly the compressed air passing into the tube F closes the check-valve F³, so that no air can pass into the compartment D through said tube F, but only through the tube E, and when the plunger J² covers the inlet of the tube E at E² no more compressed air passes into the compartments D and D' of the label-carrier C, as sufficient compressed air has already passed to said compartments for applying the label to the bottle M, and upon the closing of the tube E all the compressed air passes through the tube H into the piston-chamber G³ against the piston G² during the remainder of the downward stroke of the plunger J² for the purpose of positively and quickly driving the label-carrier C back to its position over the label-box B. The compressed air blows the label onto the bottle M, and the movement of the label-carrier C rolls the bottle, and in the rolling of said bottle by the carrier C the label B' is rolled or pressed more securely on said bottle by means of the yielding rolls L⁴, and as the rubber strips C⁵ come over the bottle M they act on said bottle and cause it to continue its turning, so that the label is securely applied to the bottle. The label-carrier continuing its rearward movement by reason of the compressed air acting on the piston G² reaches its position over the label-box B, and the plunger J², starting on its upward movement, causes another label B' to be lifted, and the operation is repeated as hereinbefore described.

The label-box, the mucilage-box, and the labeling-receptacle can be moved to any desired position on the tracks A'.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In an apparatus for labeling articles, a label-box for holding the labels, a label-carrier for transferring a label from the label-box to the article to be labeled, means for producing a vacuum in the label-carrier for moving a label from the label-box and for hold-

ing it on the label-carrier during its travel to the article to be labeled, means for moving the label-carrier from the label-box to the article to be labeled, a device located in the line of travel of the label-carrier for applying adhesive material to the label as the under side of said label passes over and in contact with said device on the travel of said label from the label-box to the article to be labeled, 5 means for applying the transferred label to the article to be labeled, means consisting of said label-carrier for rolling the article to be labeled during the application of the transferred label, and means for preventing the 10 contact of said label-carrier and said adhesive-applying device upon the return movement of the label-carrier to the label-box.

2. In an apparatus for labeling articles, a label-box for holding the labels, a label-carrier for transferring a label from the label-box to the article to be labeled, means for producing a vacuum in the label-carrier for moving a label from the label-box and for holding it on the label-carrier during its travel to 15 the article to be labeled, means for moving the label-carrier from the label-box to the article to be labeled, a device located in the line of travel of the label-carrier for applying adhesive material to the label as the under side of said label passes over and in contact with said device on the travel of said label from the label-box to the article to be labeled, means for applying the transferred label to the article to be labeled, means for rolling the article to be labeled during the application of the transferred label, means for returning the 20 label-carrier to the label-box, and means for moving said device away from contact with the bottom plate of the label-carrier during the return of the label-carrier to the label-box.

3. In an apparatus for labeling articles, a label-box for holding the labels, a label-carrier for transferring a label from the label-box to the article to be labeled, means for producing a vacuum in the label-carrier to move a label from the label-box and to hold it on the label-carrier during its travel to the article to be labeled, means for moving the label-carrier from the label-box to the article to be labeled, a device located in the line of travel of the label-carrier for applying adhesive material to the label as the under side of 25 said label passes over and in contact with said device on the travel of said label from the label-box to the article to be labeled, means for applying the transferred label to the article to be labeled, means consisting of said label-carrier for rolling the article to be labeled during the application of the transferred label, means for returning the label-carrier to the label-box, and means for preventing the contact of said label-carrier and 30 said adhesive-applying device upon the return movement of the label-carrier to the label-box.

4. In an apparatus for labeling articles, a label-box for holding the labels, a label-carrier for transferring a label from the label-box to the article to be labeled, means for moving a label from the label-box and for holding it on the label-carrier during its travel to the article to be labeled, means for moving the label-carrier from the label-box to the article to be labeled, a device located in the line of travel of the label-carrier for applying adhesive material to the label as the under side of said label passes over and in contact with said device on the travel of said label from the label-box to the article to be labeled, means for applying the transferred label to the article to be labeled, means for rolling the article to be labeled during the application of the transferred label, means for returning the label-carrier to the label-box, and means for moving said device away from contact with the bottom plate of the label-carrier during the return of the label-carrier to the label-box.

5. In an apparatus for labeling articles, a label-box for holding the labels, a label-carrier for transferring a label from the label-box to the article to be labeled, means for producing a vacuum in the label-carrier to move a label from the label-box and to hold it on the label-carrier during its travel to the article to be labeled, means for moving a label-carrier from the label-box to the article to be labeled, a device located in the line of travel of the label-carrier for applying adhesive material to the label as the under side of said label passes over and in contact with said device on the travel of said label from the label-box to the article to be labeled, means for producing an air-pressure in the label-carrier to apply the transferred label to the article to be labeled, means for rolling the article to be labeled during the application of the transferred label, means for returning the label-carrier to the label-box, and means for moving said device away from contact with the bottom plate of the label-carrier during the return of the label-carrier to the label-box.

6. In an apparatus for labeling articles, a label-box for holding the labels, a label-carrier for transferring a label from the label-box to the article to be labeled, means for producing a vacuum in the label-carrier to move the label from the label-box and to hold it on the label-carrier during its travel to the article to be labeled, means for moving the label-carrier from the label-box to the article to be labeled, a device located in the line of travel of the label-carrier for applying adhesive material to the under side of the label on its travel from the label-box to the article to be labeled, means for producing an air-pressure in the label-carrier for applying the transferred label to the article to be labeled, means for rolling the article to be labeled during the application of the transferred label, means for returning the label-carrier to the label-box.

label-box, and means for preventing the contact of said label-carrier and said adhesive-applying device upon the return movement of the label-carrier to the label-box.

- 5 7. In an apparatus for labeling articles, a label-box for holding the labels, a label-carrier for transferring a label from the label-box to the article to be labeled, means for producing a vacuum in the label-carrier for 10 moving the label from the label-box and for holding it on the label-carrier during its travel to the article to be labeled, means for moving the label-carrier from the label-box to the article to be labeled, means for returning the 15 label-carrier to the label-box, means for applying the transferred label to the article to be labeled upon the return movement of said label-carrier, means consisting of said label-carrier for rolling the article to be labeled 20 during the application of the transferred label upon the return movement of said label-carrier to the label-box, and means for preventing the contact of said label-carrier and said adhesive-applying device upon the return movement of the label-carrier to the label-box.

- 25 8. In an apparatus for labeling articles, a label-box for holding the labels, a label-carrier for transferring a label from the label-box to the article to be labeled, means for producing a vacuum in the label-carrier for moving the label from the label-box and for holding it on the label-carrier during its travel to the article to be labeled, means for moving the label-carrier from the label-box to the article to be labeled, a device located in the line of travel of the label-carrier for applying adhesive material to the under side of the label on its travel from the label-box to the article 30 to be labeled, means for returning the label-carrier to the label-box, means for applying the transferred label to the article to be labeled upon the return movement of said label-carrier, means consisting of said label-carrier for rolling the article to be labeled during the application of the transferred label upon the return movement of said label-carrier to the label-box, and means for preventing the contact of said label-carrier and 35 said adhesive-applying device upon the return movement of the label-carrier to the label-box.

- 40 9. In an apparatus for labeling articles, a label-box for holding the labels, a label-carrier for transferring a label from the label-box to the article to be labeled, means for moving the label from the label-box and for holding it on the label-carrier during its travel to the article to be labeled, means for moving the label-carrier from the label-box to the article to be labeled, a device located in the line of travel of the label-carrier for applying adhesive material to the under side of the label on its travel from the label-box to the article 45 to be labeled, means for returning the label-carrier to the label-box, means for applying the transferred label to the article to be labeled upon the return movement of said label-carrier to the label-box, and means for preventing the contact of said label-carrier and said adhesive-applying device upon the return movement of the label-carrier to the label-box.

50 beled upon the return movement of said label-carrier, means for rolling the article to be labeled during the application of the transferred label upon the return movement of said label-carrier to the label-box, and means for moving said adhesive-applying device away from contact with the bottom plate of the label-carrier during the return of the label-carrier to the label-box.

55 10. In an apparatus for labeling articles, a label-box for holding the labels, a label-carrier for transferring a label from the label-box to the article to be labeled, means for producing a vacuum to lift a label from the label-box to the label-carrier and to move the label-carrier with the label to the article to be labeled, a device located in the line of travel of the label-carrier for applying adhesive material to the under side of the label on its travel from the label-box to the article to be labeled, a receptacle for holding the article to be labeled, means for applying the transferred label to the article to be labeled, means for rolling the article to be labeled during the application of the transferred label, and means for preventing the contact of said label-carrier and said adhesive-applying device upon the return movement of the label-carrier to the label-box.

60 11. In an apparatus for labeling articles, a label-box for holding the labels, a label-carrier for transferring a label from the label-box to the article to be labeled, means for producing a vacuum to lift a label from the label-box to the label-carrier and to move the label-carrier with the label to the article to be labeled, a device located in the line of travel of the label-carrier for applying adhesive material to the under side of the label on its travel from the label-box to the article to be labeled, a receptacle for holding the article to be labeled, means for applying the transferred label to the article to be labeled and for returning the label-carrier to the label-box, means for rolling the article to be labeled during the application of the transferred label, and means for preventing the contact of said label-carrier and said adhesive-applying device upon the return movement of the label-carrier to the label-box.

65 12. In an apparatus for labeling articles, a label-box for holding the labels, a label-carrier for transferring a label from the label-box to the article to be labeled, means for producing a vacuum to lift a label from the label-box to the label-carrier and to move the label-carrier with the label to the article to be labeled, a device located in the line of travel of the label-carrier for applying adhesive material to the under side of the label on its travel from the label-box to the article to be labeled, a receptacle for holding the article to be labeled, means for producing an air-pressure to release the transferred label from the label-carrier to apply it and to return the label-carrier to the label-box, means for rolling the article to be labeled during the appli-

cation of the transferred label, and means for preventing the contact of said label-carrier and said adhesive-applying device upon the return movement of the label-carrier to the 5 label-box.

13. In an apparatus for labeling articles, a label-box for holding the labels, a label-carrier for transferring a label from the label-box to the article to be labeled, means for 10 producing a vacuum to lift a label from the label-box to the label-carrier and to move the label-carrier with the label to the article to be labeled, a device located in the line of travel of the label-carrier for applying adhesive material 15 to the under side of the label on its travel from the label-box to the article to be labeled, a receptacle for holding the article to be labeled, means for producing an air-pressure to release the transferred label from 20 the label-carrier to apply it and to return the label-carrier to the label-box, means for rolling the article to be labeled during the application of the transferred label, and means for moving said adhesive-applying device away 25 from contact with the bottom plate of the label-carrier during the return of the label-carrier from the labeling-receptacle to the label-box.

14. In an apparatus for labeling articles, a 30 label-box for holding the labels, a label-carrier for transferring a label from the label-box to the article to be labeled, means for moving the label-carrier from the label-box to the article to be labeled, means for producing a vacuum in the label-carrier during its travel to the article to be labeled, a device located in the line of travel of the label-carrier for applying adhesive material to the 35 under side of the label on its travel from the label-box to the article to be labeled, a receptacle for holding the article to be labeled, means for producing an air-pressure in the label-carrier to apply the transferred label, means for rolling the article to be labeled 40 during the application of the transferred label, means for returning the label-carrier to the label-box, and means for preventing the contact of said label-carrier and said adhesive-applying device upon the return movement 45 of the label-carrier to the label-box.

15. In an apparatus for labeling articles, a label-box for holding the labels, a label-carrier for transferring a label from the label-box to the article to be labeled, means for 50 moving the label-carrier from the label-box to the article to be labeled, means for producing a vacuum in the label-carrier to lift a label from the label-box and to hold it on the label-carrier during its travel to the article 55 to be labeled, a device located in the line of travel of the label-carrier for applying adhesive material to the under side of the label on its travel from the label-box to the article to be labeled, a receptacle for holding the article to be labeled, means for producing an air-pressure in the label-carrier to apply the transferred label, means for rolling the arti- 60

cle to be labeled during the application of the transferred label, means for returning the label-carrier to the label-box, and means for 70 moving said adhesive-applying device away from contact with the bottom plate of the label-carrier during the return of the label-carrier from the labeling-receptacle to the label-box. 75

16. In an apparatus for labeling articles, a label-box for holding the labels having an opening smaller than the size of the labels, a hollow label-carrier for transferring a label from the label-box to the article to be labeled 80 and having a perforated bottom, a support for the label-carrier in its travel, an air-pump having a piston-rod connected directly to a driving-wheel, a conduit connecting said label-carrier with said pump, a piston-chamber, 85 a piston adapted to reciprocate in said chamber and having its piston-rod connected to the label-carrier, a conduit connecting said piston-chamber with said air-pump, means for moving the labels in the label-box upwardly toward the top of said box, a device located in the line of travel of the label-carrier for applying adhesive material to the under side of the label on its travel from the label-box to the article to be labeled, said air- 90 pump being adapted during its forward stroke to produce a vacuum in the label-carrier to move a label from the label-box to the label-carrier through said opening and to hold it over said perforations and to produce a vacuum in said piston-chamber to move the label-carrier with the label to the article to be labeled, and adapted during its return stroke to produce an air-pressure in the label-carrier to apply the transferred label to the article to be labeled and to produce an air-pressure in said piston-chamber and to return said label-carrier to said label-box, means for rolling the article to be labeled during the application of the transferred label upon the return movement of said label-carrier to the label-box, and means for preventing the contact of said label-carrier and said adhesive-applying device upon the return movement of the label-carrier to the label-box. 95 100 105 110 115

17. In an apparatus for labeling articles, a label-box for holding the labels, a labeling-receptacle in which the article to be labeled is placed, yielding rollers in said receptacle on which said article is supported, a label-carrier for transferring a label from the label-box to the article to be labeled, means for moving the label from the label-box and for holding it on the label-carrier during its travel to the article to be labeled, means for moving the label-carrier from the label-box to the article to be labeled, a device located in the line of travel of the label-carrier for applying adhesive material to the label as the under side of said label passes over and in contact with said device on the travel of said label from the label-box to the article to be labeled, means consisting of said label-carrier for rolling the article to be labeled dur- 120 125 130

ing the application of the transferred label and during the travel of said label-carrier, and means for preventing the contact of said label-carrier and said adhesive-applying device upon the return movement of the label-carrier to the label-box.

18. In an apparatus for labeling articles, a label-box for holding the labels, a labeling-receptacle in which the article to be labeled is placed, yielding rollers in said receptacle on which said article is supported, a label-carrier for transferring a label from the label-box to the article to be labeled, means for producing a vacuum in the label-carrier for moving the label from the label-box and for holding it on the label-carrier during its travel to the article to be labeled, means for moving the label-carrier from the label-box to the article to be labeled, a device located in the line of travel of the label-carrier for applying adhesive material to the label as the under side of the label passes over and in contact with said device on the travel of said label from the label-box to the article to be labeled, means consisting of said label-carrier for rolling the article to be labeled during the application of the transferred label, and means for preventing the contact of said label-carrier and said adhesive-applying device upon the return movement of the label-carrier to the label-box.

19. In an apparatus for labeling articles, a label-box for holding the labels, a labeling-receptacle in which the article to be labeled is placed, yielding rollers in said receptacle on which said article is supported, means for vertically adjusting said rollers, a label-carrier for transferring a label from the label-box to the article to be labeled, means for producing a vacuum in the label-carrier for moving the label from the label-box and for holding it on the label-carrier during its travel to the article to be labeled, means for moving the label-carrier from the label-box to the article to be labeled, means for applying adhesive material to the under side of the label on its travel from the label-box to the article to be labeled, means for applying the transferred label to the article to be labeled, means for returning the label-carrier to the label-box, means for preventing the contact of said label-carrier and said adhesive-applying device upon the return movement of the label-carrier to the label-box, and means consisting of a label-carrier for rolling the article to be labeled during the application of the transferred label.

20. In an apparatus for labeling articles, a label-box for holding the labels, a labeling-receptacle in which the article to be labeled is placed, yielding rollers in said receptacle on which said article is supported, means for vertically adjusting said rollers, a label-carrier for transferring a label from the label-box to the article to be labeled, means for producing a vacuum in the label-carrier for moving the label from the label-box and for holding it on the label-carrier during its travel to the article to be labeled, means for moving the label-carrier from the label-box to the article to be labeled, means for applying adhesive material to the under side of the label on its travel from the label-box to the article to be labeled, means for applying the transferred label to the article to be labeled, means for returning the label-carrier to the label-box, and means consisting of said label-carrier for rolling the article to be labeled during the application of the transferred label.

25. In an apparatus for labeling articles, a label-box for holding the labels, a labeling-receptacle in which the article to be labeled is placed, yielding rollers in said receptacle on which said article is supported, means for vertically adjusting said rollers, a label-carrier for transferring a label from the label-box to the article to be labeled, means for producing a vacuum in the label-carrier for moving the label from the label-box and for holding it on the label-carrier during its travel to the article to be labeled, means for moving the label-carrier from the label-box to the article to be labeled, a device for applying adhesive material to the under side of the label on its travel from the label-box to the article to be labeled, means for applying the transferred label to the article to be labeled, means for returning the label-carrier to the label-box, means for preventing the contact of said label-carrier and said adhesive-applying device upon the return movement of the label-carrier to the label-box, and means consisting of a label-carrier for rolling the article to be labeled during the application of the transferred label.

30. In testimony whereof I have signed my name to this specification, in the presence of two subscribing witnesses, this 18th day of September, A. D. 1897.

CHARLES F. TEBBETTS.

Witnesses:

E. L. HARLOW,
A. L. MESSER.
